(57) **CLAIM**

The ornamental design for a travel case for biological sample detection system as shown and described.

DESCRIPTION

FIG. 1 is a top, front, left perspective view of a travel case for a biological sample detection system according to a first embodiment;

FIG. 2 is a left side view thereof;

FIG. 3 is a right side view thereof;

FIG. 4 is a top view thereof;

FIG. 5 is a bottom view thereof;

FIG. 6 is a front view thereof;

FIG. 7 is a rear view thereof;

FIG. 8 is a top, front, left perspective view of a travel case for a biological sample detection system according to a second embodiment;

FIG. 9 is a left side view thereof;

FIG. 10 is a right side view thereof;

FIG. 11 is a top view thereof;

FIG. 12 is a bottom view thereof;

FIG. 13 is a front view thereof; and,

FIG. 14 is a rear view thereof.

(Continued)

The broken lines in the drawings illustrate portions of the travel case for biological sample detection system that form no part of the claimed design.
